(57) **CLAIM**

The ornamental design for a bowed baseplate for a heat generating device, as shown and described.

(21) Appl. No.: **29/395,149**

DESCRIPTION

(22) Filed: **Dec. 5, 2011**

FIG. 1 is a top perspective view of the bowed baseplate for a heat generating component, employing our new design; FIG. 2 is a top view of FIG. 1; FIG. 3 is a bottom view of FIG. 1; FIG. 4 is a front end view of FIG. 1; FIG. 5 is a rear end view of FIG. 1; FIG. 6 is a left side view of FIG. 1; FIG. 7 is a right side view of FIG. 1; and, FIG. 8 is a magnified cross-sectional view of FIG. 2. The broken lines showing alternative cutouts are for illustrative purposes only and form no part of the claimed design.
